UNITED STATES PATENT OFFICE.

CHARLES F. RICHARDSON, OF WOONSOCKET, RHODE ISLAND, ASSIGNOR TO WM. FILENE'S SONS COMPANY, OF BOSTON, MASSACHUSETTS, A CORPORATION OF MASSACHUSETTS.

VENDING-MACHINE.

1,182,793.

Specification of Letters Patent.

Patented May 9, 1916.

Application filed February 27, 1915. Serial No. 10,892.

To all whom it may concern:

Be it known that I, CHARLES F. RICHARDSON, a citizen of the United States, and a resident of the city of Woonsocket, in the county of Providence, State of Rhode Island, have invented new and useful Improvements in Vending-Machines, of which the following is a specification.

This invention relates broadly to check 10 controlled apparatus and more specifically to coin controlled vending machines of the manually operated type.

The principal object of this invention is to construct a manually operated vending 15 machine wherein both the delivery and the coin controlled mechanisms are positively actuated to release the locking mechanism and to deliver a package.

It is also a primary object of this invention 20 to construct a manually operated vending machine in such manner that the parts will withstand excessive use and abuse without the possibility of deranging the mechanisms so that packages may be surreptitiously obtained from the package container.

A further object of this invention is to construct a manually operated vending machine 25 wherein substantially all of the primary operating elements of the device have rotary movements.

Another object of this invention is to construct a vending machine wherein the coin controlled mechanism and the delivery 35 mechanism are rotary parts having a common axis, and an intermediate device for transmitting certain forces from one mechanism to the other.

A still further object of this invention is 40 to construct a vending machine including a rotative coin controlled mechanism, and a rotary delivery mechanism with a clutch member intermediate the coin controlled mechanism and the delivery mechanism.

A still further object of this invention is 45 to construct a manually operated vending machine including a rotative coin carrier mounted upon a driving shaft and a rotative delivery mechanism mounted upon a driven shaft, both of said shafts having a common axis of rotation; and a clutch mechanism operatively connecting said shafts, said clutch mechanism being constructed to be operative during a certain portion of the 55 rotation of the driving shaft and inopera-

tive during other portions of the rotation of the said driving shaft.

Still other and further objects of this invention will in part be obvious and will in part be pointed out hereinafter in the specification following by reference to the accompanying drawings wherein like parts are designated by like characters throughout the several figures thereof.

Figure 1 is a view showing a sectional 65 elevation on substantially a vertical plane passing through the center line of the vending mechanism; the relationship of certain parts not directly within the section are indicated by dot and dash outlines. Fig. 2 is 70 an extended perspective view looking from the operating handle rearwardly to the first delivery wheel and showing the operating mechanisms separated to more clearly illustrate their operation and function. Fig. 3

is an extended perspective view of the operating mechanism looking from the delivery mechanism lock toward the operating handle. Fig. 4 is a front elevational 75 view of the coin plate showing the outline of the front plate in dot and dash lines and illustrating only the operative parts between section lines A—A and B—B, Fig. 1. Fig.

5 is a detail view showing an elevation of the parts between the section lines B—B 80 and C—C of Fig. 1. Fig. 6 is a view similar to Fig. 4 with the exception that the operating parts are illustrated in their position when a proper coin has been inserted in the 85 machine and the operating lever turned sufficiently for the coin to operate the locking mechanism to release the parts so that the machine may be actuated to deliver a

package. Fig. 7 is a view similar to Fig. 5 90 with the exception that the parts are illustrated to correspond to the rotative position of parts in Fig. 6, i. e., when the parts have been rotated sufficiently to release the locking mechanism so that the machine may be 95 actuated to deliver a package. Fig. 8 is an elevational detail view illustrating substantially the mechanisms between section lines C—C and D—D of Fig. 1, and showing the devices for unlocking or opening the package receptacle to permit a package to be delivered. Fig. 9 is a view illustrating the mechanism for closing the coin slot when the supply of packages is exhausted from the package receptacle.

The drawings, and the specification to 100 105 110

gether with the claims, all presented herewith, and constituting the present application, relate more especially to the coin control mechanism of my vending machine, the 5 delivery mechanism being more fully illustrated, described and claimed in my companion application Serial No. 34,448 filed in the United States Patent Office on the 16th day of June, 1915.

- 10 Vending machines are a mechanism adapted to be used by the general public and therefore are liable to abuse in operation, and must be constructed to guard against any possibility of rendering the mechanism operable by the introduction of strings, wires or improvised tools into the mechanism to release or unlock the same, and at the same time such machines must be so constructed as to insure operation, when a proper coin 15 or token is inserted in the machine.

The mechanism illustrated in the accompanying drawings is constructed particularly with a view to strength, to withstand severe usage and abuse. And since rotative 25 parts usually perform their function with a less degree of friction and wear than sliding or reciprocating elements, substantially all of the operative mechanism has been designed to include rotative parts. Since the 30 function of the coin released devices is nominally that of a locking mechanism to which a predetermined coin constitutes the key, and since the delivery mechanism is entirely for the purpose of delivering a package after the release of the locking mechanisms, I 35 have constructed the coin released mechanism as one group of devices and the delivery mechanism as another group of devices with a transmission or clutch intermediate 40 the said devices; the clutch being so constructed that the delivery mechanism does not begin its effective operation until the coin released mechanism has been unlocked by a proper coin.

45 From the foregoing description it will be noted that the present device meets the requirements of strength, security, and insures effective operation when a proper coin is inserted.

50 Referring now to the drawings and more particularly to Figs. 1, 2 and 4, a driving shaft 1 is journaled in a front plate 2 and carries an operating handle 4 on its forward end, which may be secured in any convenient 55 manner, as for example the pin 5. The inner side of the front plate 2 is provided with a circular recess in which is journaled the hub 6 of the circular coin plate 7. The front plate 2 is also provided with a recess to accommodate the coin plate 7, and the hub 6 of the said coin plate is of a length sufficient to provide a space between the coin plate 7 and the front plate 2, the depth of which 60 space is slightly greater than the thickness 65 of a predetermined coin. The front plate 2

is also provided with depressions constituting the coin insert chute 8 and a slug or improper coin exit 9. (See Fig. 4.) The coin plate 7 on its front surface near the upper edge thereof carries a pair of coin studs 10, 70 the inner edges or sides of which are spaced apart a distance slightly less than the diameter of a predetermined coin, so that when the proper coin is dropped through the coin insert chute 8 it will rest upon and between 75 the coin studs 10 with the upper edge of said coin slightly below the upper edge of the circular coin plate 7. A pair of segmental guards 11 are also mounted on the front surface of the coin plate and may be retained in 80 position thereon by means of securing devices such as rivets 12, and one end of each segmental guard is provided with a sharp cutting edge 14 which lies adjacent the edge of the coin plate 7, and as the coin plate is 85 revolved in a manner to be hereinafter described, one of the cutting edges 14 will pass the lower edge or side of the coin insert chute 8, while the other cutting edge 14 will pass the upper edge of the improper coin exit 90 9. In each case a rotation of the coin plate 7 will cause the said cutting edges 14 to shear any string or wire introduced into the mechanism for the purpose of attempting to trip or unlock the coin released devices. Furthermore, the outer edges of the segmental guards 11 prevent coins reaching the operating mechanism of the device when it has been turned beyond the normal position of rest. A coin cam 15 comprising an irregular shaped member 16 is secured to the front plate 2 and is retained in the space between the front surface of the coin plate 7 and the front plate 2. This coin cam being secured 100 to the front plate is therefore stationary and its outer surface is curved in such manner as to contact with the inner edge of a coin which may be retained between the coin studs 10, and when the coin plate 7 has been rotated sufficiently, the curve of the coin cam is such as to thrust outwardly the 105 said coin from between the studs 10 into the outlet coin chute 16 which leads to the coin box 17.

Referring now to Figs. 1, 3 and 4, a collar 18 carrying a locking ratchet wheel 19 is secured to the driving shaft 1 by any desirable means, such as for example the pin 20, so that the locking ratchet wheel positively rotates with the power shaft 1 and the coin plate 7. A Y-shaped coin release lever 21 is pivotally mounted, for example on the bracket 22, in such manner that the locking pawl 24 is between the limit teeth 25 and 26 on the ratchet wheel 19 and the coin contact 115 roll 27 is forced against the outer edge of the segmental guard 11 by means of the coiled spring 28.

In order to normally maintain the operating handle 4 in a vertical position a cen- 120 125 130

tralizing mechanism is provided (Fig. 3) which comprises a centralizing lever 29 pivotally mounted on a stud screw 30 that is secured to the front plate 2. A contractile 5 spring 31 normally retains the upper edge of the centralizing lever 29 in contact with the studs 32 and 34 that are set in the locking ratchet wheel 19. The stud 34 is considerably longer than the stud 32 for a reason 10 which will be hereinafter explained. The centralizing lever 29 is provided with a depending portion on which is pivotally mounted an overthrow lever 35 that is normally retained against a stop pin 36, by 15 means of the spring 37, which is also carried by the centralizing lever 29. The upper end of the overthrow lever as at 38 is curved sufficiently to permit the short stud 32 to pass thereunder, while the long stud 34 will be 20 engaged by the portion 38. By this mechanism it will be seen that the contractile spring 31 will cause the centralizing lever 29 to rotate the coin plate 7 and the ratchet wheel 19 until the upper edge of the centralizing lever bears equally against the lower 25 part of the studs 32 and 34 thus holding the operating handle 4 in a vertical position. The stud 34 will engage with the portion 38 of the overthrow lever 35 as the operating 30 handle 4 is rotated clockwise and the overthrow lever 35 will be turned on its pivot to stretch the spring 37 so that if the handle 4 should be released with the pin 34 directly beneath the driving shaft 1, the extended 35 spring 37 will contract thereby turning the overthrow lever and moving the stud 34 from beneath the direct vertical line including the axis of the power shaft and the axis of the stud 34, so that the parts will be 40 thrown off "dead center" and the centralizing lever will return the several parts to their normal position. Thus it will be seen that the function of the devices just described is that of maintaining the coin controlled 45 parts in normal position and obviating the possibility of the device stopping on "dead center."

The parts previously specified relate to the coin control elements which may be associated with various types of delivery mechanism, providing a suitable transmission device is constructed intermediate the coin controlled mechanisms and the delivery mechanism. In the present case the intermediate 50 or transmission mechanism comprises a clutch including a collar 39 secured to the driving shaft 1 to constitute the hub on which a clutch arm 40 is fixedly secured. The clutch arm 40 carries a clutch pawl 41 which is maintained in engagement, by 55 means of a spring 48, with a clutch disk 42 that is fixedly mounted upon the driven or delivery shaft 44. In the present case in order to obtain a secure and convenient bearing for the delivery shaft 44, I have pro-

vided the inner end of the driving shaft 1 with a recess, such as at 45, and have also provided the delivery shaft 44 with a reduced portion or stud 46 which is constructed to accurately fit the recess 45 thereby axially 70 alining the driving shaft 1 with the driven shaft 44. The clutch disk 42 is provided with diametrically disposed notches 47 with which the end of the clutch pawl 41 is adapted to coöperate, due to the spring 48, 75 to transmit power from the driving shaft to the driven shaft, when the driving shaft is rotated in a clockwise direction. In the type of delivery mechanism which I have herein illustrated, it is desirable that the 80 delivery or driven shaft make but one-half revolution while the power or driving shaft makes a complete revolution. Therefore, I have provided a release cam 49 comprising a stationary member secured to the front 85 plate 2 and having its operative cam face 50 in the path of rotation of the outer end of the clutch pawl 41. The parts are so arranged that as the clutch arm 40 rotates, thereby carrying the clutch pawl into engagement with a notch 47, the said clutch pawl will be released from said notch by contact of the outer end 51 of the pawl with the operative cam face 50 of the releasing cam 49, when the delivery or driven shaft 88 44 has been rotated through substantially one-half revolution.

As it is desirable in vending machines to prevent the delivery mechanism being operated by insertion of devices through the exit 100 chute through which the goods are delivered, I have provided a locking mechanism for securing the delivery devices in normal position. The specific locking mechanism herein illustrated comprises a delivery wheel 105 lock 52 pivotally mounted on a short shaft 54 that is supported in bosses 55 which may be formed integral with the main casing 56. The delivery wheel lock includes a locking arm 57 provided with a notch adapted to 110 engage one of the locking stop pins 58 which are carried by the forward delivery wheel 59. A small spring 60 normally urges the locking arm 57 toward the center of the delivery wheel and a short cylinder 61 is provided on the delivery wheel 59 to prevent the locking arm from being moved beyond desired limits, after the parts have been rotated beyond normal position. It is necessary that the delivery wheel lock be released prior to the movement of the delivery 120 or driven shaft, and therefore I have provided the clutch arm 40 with an offset 62 that coöperates with the release arm 64 which is preferably formed integral with the 125 delivery wheel lock 52.

The type of delivery mechanism herein illustrated comprises a pair of delivery wheels 59 and 65, both of which have substantially the same irregular periphery and 130

are in each case provided with a pair of expulsion projections 66. Each delivery wheel is also provided with a substantially flat portion 67 upon which a package, as for example X, to be delivered, may rest. Normally I prefer that the bottom package may be supported upon L-shaped brackets 68 and also upon a hinged gate 69 that is controlled by means of a double S-shaped cam 70 which is secured to the delivery or driven shaft 44. The hinged gate 69 is provided with an anti-friction roller 71 which coöperates with the cam 70 in such manner as to permit the gate 69 to be dropped or opened when the delivery wheel is turned. This delivery mechanism is more fully described and shown in my companion application.

As it is desirable to prevent the insertion of coins when the magazine 72, indicated in dotted lines in Fig. 1, is empty, I have provided a coin slot closure comprising a plate 74 slotted as at 75 to provide a guideway which coöperates with the stub screws 76 that are threaded into the bosses or posts 77, which I have in the present case formed integral with the upper part of the main casing 56. The plate 74 carries at its inner end a shoe 78 which, by means of the spring 79 is caused to lightly bear against packages in the magazine holder and thereby maintain the notch 80 adjacent the coin insert chute 8. When the last package leaves the magazine it will be noted that the spring 79 will be free to contract and thereby move the plate 74 inwardly so that its outer end is substantially flush with the front plate 2 and so that the notch 80 is no longer adjacent the coin chute 8, but a portion of the coin chute is obstructed by means of the outer end of the plate 74 thereby effectively closing the chute in such manner as to prevent the insertion of a coin.

The coin chute 8 previously referred to is of a width substantially the diameter of a proper predetermined coin so that it is impossible to introduce into the device a coin larger than is intended to be used in the machine thereby obviating the possibility of the mechanism being jammed by the coin resting on the studs 10 with the edge of the coin standing above the upper edge of the coin plate 7. If an improper coin of a diameter less than a predetermined coin be introduced into the machine it will fall between the studs 10, and taking the path indicated by the short arrows in Figs. 2 and 4, will pass out through the outlet chute 16 and be returned to the operator. It will be noted that the operating handle 2 may at any time be turned a limited amount, *i. e.*, the distance between the limit teeth 25 and 26. This movement however, is not sufficient to actuate any of the mechanisms other than the centralizing

lever. The movement is not sufficient to completely unlock the delivery wheels.

If a proper coin be introduced into the machine and the operating handle turned in a clockwise direction the coin will engage 76 on its inner edge with the coin cam 15 and in passing beneath the coin contact roll 27 will force the roll outwardly (see Fig. 6) thereby removing the locking pawl 24 from the path of the limit tooth 26, (the other 75 notches in the locking ratchet wheel 19 are one-way notches permitting the locking wheel to be turned in a clockwise direction but through the locking pawl 24 preventing turning in a counter-clockwise direction,) 80 and the operating handle may be turned one complete revolution. The turning of the operating handle after the parts have been released will cause the delivery wheels to be unlocked and the clutch pawl to engage 85 the clutch disk so that further movement will turn the delivery wheels. As the turning movement continues the driven shaft and the driving shaft rotate together thereby causing the S-shaped cam 70 to be turned 90 sufficiently to allow the outer end of the hinged gate 69 to drop so that the package X will rest upon the flat portion 67 of the delivery wheels. A further rotating movement will cause the expulsion projections 95 66 to engage the side of the package to expel the same from the package magazine and thereby delivering the said package to the operator. A continued turning of the operating handle restores the coin plate 7 100 and the coin controlled mechanisms to normal position and permits the pawl 24 to drop between the limit teeth 25 and 26 of the locking ratchet wheel thereby locking the parts against operation until another 105 proper coin is inserted. The construction is such that during the time when the space between the lower ends of the segmental guards 11 is passing beneath the coin contact roll 27, the pawl 24 is riding on the 110 outer edge of the locking ratchet wheel, *i. e.*, on the end of one of the teeth in the said ratchet wheel thus preventing the said roll 27 from dropping into the specified space. 115

From the foregoing it will be noted that the desiderata reached by the present invention may be carried out in mechanisms comprising the equivalents of the various parts herein illustrated, which are departures from the specific mechanisms illustrated, but which do not depart from the intent and scope of the present invention. In view of this fact I desire that the particular devices herewith shown and herein described be considered as illustrative and not to be taken in a limiting sense. 120 125

Having thus described my invention what I claim is:—

1. In a device of the character described, 130

- in combination, a driving shaft, a circular coin plate, coin studs mounted on said coin plate with the space between said studs slightly less than the diameter of a predetermined coin, segmental guards carried by said coin plate and terminating adjacent said coin studs, a locking ratchet wheel carried by said driving shaft, a coin release lever provided with two arms, a locking pawl formed on one of said arms and adapted to coöperate with said ratchet wheel, a coin contact roll mounted on the other arm, said contact roll being in the path of a predetermined coin when said coin is in position on the coin studs and adapted by contact with said coin to render said locking pawl ineffective to lock said ratchet wheel, and means to rotate said driving shaft.
2. In a device of the character described, in combination, a driving shaft, a circular coin plate fixedly mounted on said driving shaft, means carried by said coin plate to receive and support a predetermined coin, segmental guards on said coin plate, a front plate, said front plate being provided with a coin chute, cutting edges formed on said segmental guards, a locking ratchet wheel carried by said driving shaft, a coin release lever provided with a pawl coöoperating with said ratchet wheel, means constructed to coöperate with a predetermined coin to render said pawl ineffective when said driving shaft has been rotated through a predetermined distance, and means to rotate said driving shaft.
3. In a device of the character described, in combination, a front plate provided with a circular recess, a driving shaft journaled in said front plate, a rotatable device comprising a circular disk fitting within a portion of the recess in said front plate and adapted to receive and carry a predetermined coin, a locking ratchet wheel carried by said driving shaft, means coöoperating with said locking ratchet wheel to prevent said driving shaft turning more than a predetermined distance, and mechanism constructed to coöperate with a predetermined coin to render said last mentioned means ineffective to lock said ratchet wheel prior to a complete revolution of said driving shaft, and means to rotate said driving shaft.
4. In a device of the character described, in combination, a front plate provided with a circular recess therein, a driving shaft, a circular coin plate fixedly mounted upon said driving shaft, said circular coin plate fitting within the circular recess in the said front plate and having the back face of said coin plate substantially flush with the back face of the front plate, coin studs mounted on the front face of said coin plate with the space between said studs slightly less than the diameter of a predetermined coin, locking means adjacent the back face of said coin plate normally permitting said coin plate to rotate a predetermined distance, and means constructed to coöperate with a predetermined coin to permit said coin plate to rotate one complete revolution.
5. In a device of the character described, the combination of a driving shaft, a coin plate, a pair of coin studs mounted upon said coin plate in such manner as to support a predetermined coin with a portion of the coin extending below said studs, a pair of segmental guard members terminating adjacent said coin studs, and a stationary cam adapted to coöperate with the edge of a predetermined coin nearest the driving shaft to eject said coin from between said studs when said coin plate has been rotated through a predetermined distance.
6. In a device of the character described, in combination, a front plate provided with a circular recess on the back face thereof, a driving shaft, a circular coin plate fixedly mounted upon said driving shaft fitting within the circular recess in said front plate with the back faces of said plate substantially flush, a pair of segmental guard members mounted upon said coin plate on the front face thereof and having their ends spaced apart, and means carried by said coin plate to receive and retain a predetermined coin, said guard members being adapted to prevent a coin from reaching said coin retaining means when said coin plate is rotated beyond normal position.
7. In a device of the character described, in combination, a driving shaft, a circular coin plate fixedly mounted upon said driving shaft, a pair of segmental guard members mounted upon said coin plate and having their ends spaced apart to provide openings on diametrically opposite sides of said coin plate, a pair of coin studs located adjacent the openings between the upper ends of said segmental guard members, said coin studs being spaced apart slightly less than the diameter of a predetermined coin to permit coins of a lesser size to pass between said coin studs and pass out through the lower opening between the lower ends of said guard members, and a stationary cam constructed to eject a predetermined coin from between said coin studs when said coin plate is rotated through a predetermined distance.
8. In a device of the character described, the combination of a driving shaft, a coin plate, a pair of coin studs mounted upon said coin plate in such manner as to support a predetermined coin with the outer edge of said coin slightly below the outer edge of said coin plate, a pair of segmental guard members, a knife edge on the advancing end of each segmental guard, and a front plate

provided with an inlet chute terminating adjacent the path of said knife edges when said circular coin plate is rotated.

9. In a device of the character described in combination, a main frame, a front plate detachably secured to said main frame and provided with a circular recess on the back face thereof, a coin plate comprising a circular disk fitting within the recess in said front plate so that the back faces of said plate are substantially flush, a pair of studs mounted on the front face of said coin plate with the distance between said studs slightly less than the diameter of a predetermined coin, means for moving said coin plate, locking means for limiting said movement, said locking means including a device adapted to contact with a proper coin supported between said studs in such manner that further movement of said coin plate renders said locking devices temporarily ineffective, said locking devices again becoming effective when a complete cycle of operation has been completed by said coin plate, and a stationary cam carried by said front plate for ejecting said coin after the coöperation of said coin with the locking devices to release the same.

10. In a device of the character described in combination, a circular coin plate, a pair of coin supporting studs mounted upon one side of said coin plate, a locking ratchet wheel mounted upon the other side of said coin plate, a locking pawl coöoperating with said ratchet wheel to normally limit the movement of said parts to less than one cycle of operations, a release roll connected to said locking pawl and extending over the edge of said coin plate into the path of a normal coin supported on said studs in such manner that the contact of said coin with said roll lifts said locking pawl from said ratchet wheel, and a stationary cam constructed to eject said coin from between said studs after the said coin has coöperated with the release roll.

11. In a device of the character described in combination, a driving shaft, a coin plate fixedly mounted upon said driving shaft, a pair of coin studs upon one side of said coin plate, a pair of segmental guards terminating adjacent said studs, said guards being also mounted upon said coin plate, a ratchet wheel upon the other side of said coin plate, said ratchet wheel being provided with a pair of locking teeth, a locking pawl normally retained between said locking teeth, a contact roll operatively connected with said locking pawl and normally resting against the outer edge of one of said segmental guards, said contact roll being in the path of a predetermined coin supported on said studs when said coin plate is rotated so that the con-

tact of the coin with the contact roll releases said locking pawl from between the said locking teeth and enables said locking pawl to coöperate with the ratchet teeth thereby preventing reverse rotation of the parts after the coin plate has rotated a predetermined distance, and a cam for ejecting the coin after it has coöperated with the contact roll.

12. In a coin controlled vending machine, the combination of a rotatable coin carrier, a driving shaft upon which said coin carrier is fixedly mounted, a pair of studs operatively connected with said driving shaft, a pivoted bar, a spring normally retaining said bar in contact with said studs, and a pivoted overthrow lever mounted on said bar, a spring coöoperating with said overthrow lever to enable said overthrow lever to coöperate with one of said studs to prevent said rotatable coin carrier stopping on dead center.

13. In a coin controlled vending machine in combination, a rotatable coin carrier, a centralizing device for normally maintaining said coin carrier in a predetermined position of rotation, and means for rotating said coin carrier beyond a position of dead center to enable said centralizing means to be effective.

14. In a coin controlled vending machine in combination, a rotatable coin carrier, a pair of centralizing studs operatively connected with said coin carrier, one of said studs being longer than the other, a centralizing bar, means for normally maintaining said centralizing bar in contact with both of said studs, and an overthrow lever adapted to contact with the longer stud, and to move said stud in a rotative direction from beneath the axis of rotation of the coin carrier to enable said centralizing bar to be effective to turn said rotatable coin carrier to a predetermined position.

15. In a coin controlled vending machine in combination, a power shaft, a driven shaft axially alined with said power shaft, a coin controlled lock permitting said power shaft to make one complete revolution when said lock is actuated by a predetermined coin, a lock for said driven shaft, and means to release the lock for the driven shaft to enable the driven shaft to make one-half revolution when the power shaft is making one revolution, and means to transmit power from said power shaft to said driven shaft.

16. In a coin controlled vending machine in combination, a driving shaft, a driven shaft axially alined with said driving shaft, a clutch for transmitting power from said driving shaft to said driven shaft, coin controlled lock for normally limiting the movement of said driving shaft to less than one complete revolution, means for releasing said coin controlled lock when a prede-

terminated coin is introduced therein to enable said power shaft to make one complete revolution, and a cam for controlling the effective operation of said clutch to permit 5 said clutch to be effective to transmit power during substantially one-half of the revolution of the power shaft.

17. In a coin controlled vending machine in combination, a driving shaft, a driven shaft axially alined with said driving shaft, a rotatable coin carrier mounted upon said driving shaft, a coin controlled lock co-operative with said coin carrier to be rendered ineffective when said coin carrier has 15 rotated a predetermined distance with a proper coin carried thereby, a clutch intermediate said driving shaft and said driven shaft to drive said driven shaft during a portion of the revolution of the driving 20 shaft, and means to render said clutch inoperative when said driven shaft has been rotated through substantially one-half a revolution.

18. In a vending machine in combination, 25 a container for articles to be vended, delivery mechanism for ejecting a predetermined article from said container, a lock normally preventing the actuation of said delivery mechanism, a coin controlled driving mechanism including a coin controlled lock, means actuated by the driving mechanism 30

and independent of the coin for releasing said first mentioned lock, and means for transmitting power from said coin controlled driving mechanism to said delivery 35 mechanism.

19. In a coin controlled vending machine in combination, a machine frame having a portion of its side wall substantially semi-cylindrical, a front plate comprising an end 40 cover for said frame and extending at right angles to the axis of said semi-cylindrical portion, coin controlled devices mounted upon and being removable as an entirety with the front plate, said coin controlled devices including a driving shaft journaled in said front plate and provided on its inner end with a bearing opening, a driven shaft axially alined with said driving shaft and having one end journaled in the main frame 45 and the other end journaled in the driving shaft, rotary delivery devices carried by said driven shaft, a vertical magazine carried by the upper portion of said frame, the operative parts being constructed and arranged to be readily removed when said front plate is removed. 50 55
